UNITED STATES PATENT OFFICE.

JOHN NEY, OF SHERIDAN, CALIFORNIA.

RAIL-CO尤LING AND BED-PLATE.

SPECIFICATION forming part of Letters Patent No. 268,928, dated December 12, 1882.

Application filed June 12, 1882. (No model.)

To all whom it may concern:

Be it known that I, JOHN NEY, of Sheridan, county of Placer, State of California, have invented an Improved Rail-Coupling and Bed-Plate; and I do hereby declare the following to be a full, clear, and exact description thereof.

My invention relates to a novel rail-coupling and bed-plate for railways; and it consists in a peculiar cap, fitting over the meeting ends or joints of the rails and bolted down to a peculiar-jointed bed-plate, the whole device being spiked to the ties below, as will hereinafter fully appear.

The object of my invention is to provide a coupling of sufficient strength to hold the rails and of sufficient stiffness to form a bridge over the joint when the ends of the rails sink, this stiffness being the result not only of the peculiar cap, but of the bed-plate to which it is bolted.

Referring to the accompanying drawings, Figure 1 is a perspective. Fig. 2 is a section on the line 1 2, Fig. 3; Fig. 3, a longitudinal section of the coupling cap and plate A; Fig. 25 4, an elevation of the rail E; Fig. 5, a plan showing bottom of plate A.

A represents the bed-plate. This consists of two pieces or sections, with side flanges, a, framed into each other and pivoted together 30 by means of a cross-bolt, a', passing through the overlapping edges.

B represents the coupling-cap. This is shaped somewhat like an ordinary T-rail, having the rolling-surface b, a hollow or recessed body or core, b', and sloping flanges b². These flanges lie between the side flanges, a, of the bed-plate, and have secured to them or formed with them ears b³, which extend down into apertures or sockets in the bed-plate. Cross-40 bolts c pass through the bed-plate and through the ears b³ from side to side, thus holding the cap B down to the bed-plate.

Let E E represent a portion of meeting-rails. These are ordinary T-rails with a portion of the ball or rolling-surface cut away down to the body of the rail. The ends of the rail are fitted into the socket of the cap, their flanges passing under the flange b² of the cap between them and the bed-plate, and their bodies pass

ing into the grooved or recessed body b' of 50 said cap. Their ends meet at the middle, and their rolling-surfaces continue the even plane of the rolling-surface of the cap.

Dare spikes driven down through the flanges b² of the cap, through the edges of the flanges 55 of the rails, and through the bed-plate into the cross-tie below.

E are bolts driven through the bodies or core of the cap and the rails and secured by nuts, as shown. These nuts are locked in position 60 by the heads of spikes D, thus providing increased security.

In the ordinary forms of coupling, when the ends of the rails sink a depression is formed and the surface becomes uneven, causing the 65 jarring of the car as it passes; but the effect of my construction is to remedy this difficulty.

The joining-cap B will always stay with the rails, and if any sinking occurs it will be all together, the surface still remaining even. No 70 separation can occur at the joint, and the possible sinking is provided for by the jointed bed-plate, which, by being adapted to yield at its middle, may conform itself to any alterations 75 and still hold the cap B straight. The arrangement of bolts is to the best advantage in holding all the parts together and in securing them firmly to the road-bed. The cap B may be made of any suitable length, and may be placed on any part of the rail to repair it 80 when necessary.

Having thus described my invention, what I claim as new, and desire to secure by Letters Patent, is—

A combined rail coupling and bed-plate consisting of the two-part jointed bed-plate A, the coupling-cap B, having a rolling-surface, b, a hollow or grooved body, b', flanges b², and ears b³, said cap being secured to the bed-plate by bolts c, and the rails E E, fitting within said cap, 85 and bolted therein, as shown, the whole device being secured to the road-bed by spikes D, substantially as herein described.

In witness whereof I hereunto set my hand.
JOHN NEY.
